UNITED STATES PATENT OFFICE

EDWARD B. WILDER, OF ST. LOUIS, BRYDON BERTRAM BAKER, OF UNIVERSITY CITY, AND WENTWORTH WILDER, OF ST. LOUIS, MISSOURI, ASSIGNORS TO WILDER MANUFACTURING COMPANY, OF ST. LOUIS, MISSOURI, A CORPORATION OF MISSOURI

DESIGN FOR A TOY GLIDER

Application filed January 13, 1930. Serial No. 34,114. Term of patent 7 years.

To all whom it may concern:

Be it known that we, EDWARD B. WILDER, BRYDON BERTRAM BAKER, and WENTWORTH WILDER, citizens of the United States, and residents of St. Louis, Missouri, University City, Missouri, and St. Louis, Missouri, respectively, have invented a new, original, and ornamental Design for a Toy Glider, of which the following is a specification, reference being had to the accompanying drawing, forming part hereof, in which—

Fig. 1 is a plan view of a toy glider showing our new design;

Fig. 2 is a side elevation; and,
Fig. 3 is a front elevation.

We claim:

The ornamental design for a toy glider, substantially as shown.

In testimony whereof, we have signed our names to this specification this 10th day of January, 1930.

EDWARD B. WILDER.
BRYDON BERTRAM BAKER.
WENTWORTH WILDER.
